Inventor: John B. Hawley Jr.
by *James* & *James* Atty's.

UNITED STATES PATENT OFFICE.

JOHN B. HAWLEY, JR., OF COLORADO SPRINGS, COLORADO.

TURNTABLE AND THE LIKE.

Application filed February 12, 1923. Serial No. 618,447.

To all whom it may concern:

Be it known that I, JOHN B. HAWLEY, Jr., a citizen of the United States, residing at Colorado Springs, in the county of El Paso and State of Colorado, have invented 5 certain new and useful Improvements in Turntables and the like, of which the following is a specification.

This invention has to do with improvements in turn-tables. The invention has 10 reference particularly to certain improvements in turn-tables for turning relatively light vehicles, such as automobiles, trucks, tractors, etc. Nevertheless, it will appear 15 that the features of the invention are not limited to this particular or to any other particular class of service.

One of the objects of the invention is to provide a turn-table of small size and compact form which can be conveniently used 20 in connection with garages and storage places for vehicles in comparatively small spaces.

Another object of the invention is to provide 25 a turn-table construction which is relatively light and cheap to build and install.

Another object of the invention is to provide 30 a turn-table arrangement such that it may be operated by the vehicle itself to perform the turning operation without the use or special provision of any outside source of power or turning medium. In this connection a further object is to apply the turning 35 force by the use of the power plant of the vehicle operating through the medium of its usual transmission and differential mechanisms.

A further object of the invention is to make provision for the automatic restoration 40 of the turn-table to its initial position after it has been used during the turning operation, so that it will then be ready for another turning operation in the regular course of use.

45 Other objects and uses of the invention will appear from a detailed description of the same, which consists in the features of construction and combinations of parts hereinafter described and claimed.

50 In the drawing:

Figure 1 shows a plan view of a turn-table embodying the features of the present invention, together with a suitable approach thereto from the road way. In this figure 55 the normal position of the turn-table is

shown by full lines and the turned position by means of dotted lines;

Fig. 2 shows a longitudinal section taken on the line 2—2 of Fig. 1, looking in the direction of the arrows, on enlarged scale; 60

Fig. 3 shows a fragmentary section on the line 3—3 of Fig. 1, looking in the direction of the arrows; and

Fig. 4 shows a fragmentary horizontal section taken on the line 4—4 of Fig. 2, looking in the direction of the arrows. 65

The turn-table of the present invention includes a relatively small platform which is mounted to travel in a curved, and preferably a circular path, being preferably located upon a track way of the proper curvature. Furthermore, this relatively small platform is preferably radially connected to a central pivotal point so that it will travel 70 in a true circle around the pivotal point as 75 a center.

It is intended that the front wheels of the vehicle should be carried by this platform, and that one of the rear wheels should be held stationary substantially at the pivotal point, the other rear wheel traveling in a circular path about the pivotal point during the turning operation. For this purpose any suitable power may be used, but by applying the power of the vehicle itself 80 with the transmission mechanism thrown into the reverse, a pull will be exerted causing the platform to travel around its circular path thereby turning the vehicle. 85

In the particular construction shown in 90 the drawing, I have illustrated a platform 5, preferably of concrete or other suitable floor material in the central portion of which there is a hub pedestal 6. Upon this pedestal is pivotally mounted a central hub 95 member 7, a pivot point 8 of suitable arrangement, such as a king pin being provided for the member 7. It is also preferred that the hub member 7 be provided with suitable rollers 9 working on the pedestal 100 6 so as to allow easy rotation.

Partially encircling the hub member 7 is a curved track 10. A platform 11 is mounted to travel on this track, as by means of flanged wheels 12. The platform 11 is 105 also preferably guided by means of one or more radial arms 13 connecting it to the hub member 7. These arms will not only serve to assist in guiding the platform 11 during its travel, but will also assist in 110

preventing any lateral displacement of the platform from the track, and will also cause the hub member 7 to turn on the king pin in harmony with the platform movements.

5 It is intended that a vehicle to be turned should be driven with its front wheels 14 onto the platform 11, and with one of its rear wheels 15 upon the hub member 7. The other rear wheel 16 is intended to travel 10 on the platform 5, which for this purpose should be relatively smooth and of a material which will give adequate traction.

Upon locking the wheel 15 against rotation and applying power to the wheel 16 in 15 reverse, a turning effort will be exerted causing the vehicle to travel backwardly around the wheel 15 as a center, as shown by the dotted lines 17 of Fig. 1. This will cause a lateral displacement of the platform 20 11 around the trackway 10 until the platform reaches an end stop 18 located at a point corresponding to the termination of the turn movement.

The vehicle in reaching the initial position will travel across the rail 10, and in 25 order to facilitate this operation the rail may either be depressed so as to bring its top surface practically flush with the platform 5, or else suitable approaches 19 and 30 20 may be formed at the sides of the rail, as shown in the detail of Fig. 3.

Similarly, to facilitate the driving of the front wheels up onto or down from the platform 11, this platform may be provided 35 with a slanting approach 21, as clearly shown in Fig. 2.

Any suitable arrangement may be adopted 40 for locking the rear wheel 15 against rotation during the turning movement. A convenient arrangement is that illustrated, in which the hub member 7 is provided with a central cup shaped depression 22 into which the wheel 15 may be driven and 45 where it will be held with sufficient firmness to ordinarily perform the turning operation.

Also in order to facilitate driving the wheel 15 into place within the cup 22, the 50 peripheral portions of the pedestal and of the hub member 7 may be beveled or given a slant, as illustrated in Fig. 2.

After the turning operation has been completed, the platform 11 should return automatically to its initial position as limited 55 by an end stop 23. For this purpose, I have illustrated a spring 24 within a pocket 25 in the lower portion of the hub member, which spring will be placed under tension as the platform travels towards the 60 end stop 18, and will exert a sufficient pull to restore the platform to the end stop 23 after the vehicle has been driven away.

It will be observed that the vehicle is 65 driven in along one line of travel and afterwards leaves along another line of travel

which is laterally displaced a distance substantially equal to the distance between the wheels of the vehicle itself. I have, therefore, illustrated an approach 26 which is widened at a point adjacent to the turn 70 table sufficiently to enable the vehicle to be driven in and out without difficulty notwithstanding this lateral displacement during the turning operation.

While I have herein shown and described 75 only certain embodiments of the features of my present invention, still I do not limit myself to the same except as I may do so in the claims.

I claim:

1. In a turn-table, the combination of a central wheel support pivoted for rotation about a central axis, a circular trackway extending around said wheel support as an axis, a platform journaled upon said track, 85 a radial connection from the central wheel support to the platform, an end stop at each end of said track, a spring for operating on the wheel support to turn the same and restore the platform to its initial position 90 against one of said stops, a suitable approach adjacent to the other stop, and a floor between the central wheel support and the track, whereby when the front wheels of a vehicle are carried by the platform one of 95 the rear wheels may be carried by the wheel support and the other rear wheel may travel on the floor, substantially as described.

2. In a turn-table, the combination of a central wheel support pivoted for rotation 100 about a central axis, a circular trackway extending around said wheel support as an axis, a platform journaled upon said track, a radial connection from the central wheel support to the platform, an end stop at each end 105 of said track, means for returning the platform to its initial position against one of said stops, a suitable approach adjacent to the other stop, and a floor between the central wheel support and the track, whereby when 110 the front wheels of a vehicle are carried by the platform one of the rear wheels may be carried by the wheel support and the other rear wheel may travel on the floor, substantially as described.

3. In a turn-table, the combination of a central wheel support pivoted for rotation about a central axis, a circular trackway extending around said wheel support as an axis, a platform journaled upon said track, 120 a radial connection from the central wheel support to the platform, a suitable approach adjacent to one end of the track, and a floor between the central wheel support and the track, whereby when the front wheels 125 of the vehicle are carried by the platform one of the rear wheels may be carried by the wheel support and the other rear wheel may travel on the floor, substantially as described.

130

4. In a turn-table the combination of a central wheel support pivoted for rotation about a central axis, a traveling platform, a radial connection from the central wheel support to the platform, to compel the platform to travel in a circular path about the central wheel support, a suitable approach adjacent to the wheel support and platform, and a floor adjacent to the central wheel support, whereby when the front wheels of the vehicle are carried by the platform, one of the rear wheels may be carried by the wheel support and the other rear wheel may travel on the floor, substantially as described.
5. In a turn-table, the combination of a central wheel support pivoted for rotation about a central axis, a traveling platform, means for causing the platform to travel in a circular path around said central wheel support as an axis, means tending to restore the platform to the initial position, and a floor between the central wheel support and the path of travel of the platform, whereby when the front wheels of the vehicle are carried by the platform, one of the rear wheels may be carried by the wheel support and the other rear wheel may travel on the floor, substantially as described.

JOHN B. HAWLEY, JR.
